(57) **CLAIM**

The ornamental design for pliers, as shown and described.

DESCRIPTION

FIG. 1 is a front and left side perspective view of pliers, showing one embodiment of our new design;

FIG. 2 is a rear view thereof;

FIG. 3 is a left side view thereof;

FIG. 4 is a front view thereof;

FIG. 5 is a right side view thereof;

FIG. 6 is a top view thereof;

FIG. 7 is a bottom view thereof;

FIG. 8 is a front and left side perspective view of pliers, showing another embodiment of our new design;

FIG. 9 is a rear view thereof;

FIG. 10 is a left side view thereof;

FIG. 11 is a front view thereof;

FIG. 12 is a right side view thereof;

FIG. 13 is a top view thereof;

FIG. 14 is a bottom view thereof;

FIG. 15 is a front and left side perspective view of pliers, showing another embodiment of our new design;

FIG. 16 is a rear view thereof;

FIG. 17 is a left side view thereof;

FIG. 18 is a front view thereof;

FIG. 19 is a right side view thereof;

FIG. 20 is a top view thereof;

FIG. 21 is a bottom view thereof;

FIG. 22 is a front and left side perspective view of pliers, showing another embodiment of our new design;

FIG. 23 is a rear view thereof;

FIG. 24 is a left side view thereof;

FIG. 25 is a front view thereof;

FIG. 26 is a right side view thereof;

FIG. 27 is a top view thereof; and,

FIG. 28 is a bottom view thereof.

The features shown in broken lines show portions of the pliers that form no part of the claimed design.

1 Claim, 28 Drawing Sheets
